Primary Examiner — Aula Soroush*(74) Attorney, Agent, or Firm* — Brett A. SchenckCLAIM

The ornamental design for a cat scratcher, as shown and described.

DESCRIPTION

FIG. 1 is a front, top and right perspective view of a cat scratcher, showing my new design;

FIG. 2 is a rear, top and right perspective view thereof;

FIG. 3 is a front view thereof;

FIG. 4 is a right view thereof;

FIG. 5 is a left view thereof;

FIG. 6 is a top view thereof;

FIG. 7 is a bottom view thereof; and,

FIG. 8 is a rear view thereof.

The broken lines on the periphery of the sisal pad represent stitching. The other broken lines on the end caps and rear portions of the cat scratcher form no part of the claimed design.
